VARIABLE BAND WIDTH AMPLIFIER

Horst Rothe and Werner Kleen, Berlin, Germany, assignors to Telefunken Gesellschaft für Drahtlose Telegraphie m. b. H., Berlin, Germany, a corporation of Germany

Application June 3, 1937, Serial No. 146,133
In Germany June 23, 1936

3 Claims. (Cl. 179—171)

The invention relates to an amplifier circuit in which the band width is varied by varying the inner resistance of the tube in whose plate circuit the resonant circuit to be influenced, is inserted.

It is often required that amplifiers operating with selective frequency, more especially high frequency and intermediate frequency amplifiers, be so designed that the degree of selectivity, i. e. the band width of the admitted frequency range, can be varied by simple means within certain, and often very wide, limits. It would be desirable to maintain, at this variation in the band width, the degree of amplification constant at least to a certain degree. This condition is fulfilled by the present invention.

A number of circuits are known in which the desired degree of amplification of a stage is obtained by varying an operating potential of the respective tube, for instance the control grid potential, or the screen grid potential. Furthermore, a control of the amplification can be accomplished, as is known, by influencing the inner resistance of the tube. If in these arrangements a variation in the band width was obtained simultaneously with the control of the amplification, this was not the purpose intended by the measures taken, and more particularly, the control of the amplification has not been carried out with special consideration to the band width variation. It is, also, known to control the band width by influencing the inner resistance of a pentode with the aid of a variation of the retarding grid (suppressor grid) potential. The more negative the retarding grid of a pentode is made, the lower becomes the inner resistance. But with this kind of control it is entirely impossible to maintain the degree of amplification constant during the control performance; not even to a fair degree.

In accordance with the invention, a variation of the band width of the frequency range admitted in an amplifier stage achieved by varying the inner resistance of the amplifier tube in whose plate circuit a resonant circuit is inserted.

For a better understanding of the invention, several points regarding the inner resistance of a tube operating with what has been termed "current distribution" will be considered. A tube is said to be operated with "current distribution" when the cathode current divides between the screen and plate electrodes in accordance with the instantaneous plate potential. For the inner resistance of a pentode or of a screen grid tube

free of secondary emission, there exists, as is known, the following equation:

$$R_i = \frac{b \cdot U_a}{J_a}$$

wherein b represents the constant of the inner resistance determined by the construction of the electrode system of the tube; U_a designates the plate voltage; and J_a is the plate current (see the "Journal 'Die Telefunkenröhre'" of April 1936). The inner resistance thus becomes the higher, the higher the plate potential and the smaller the plate current. The value of the screen grid potential has no direct influence upon the inner resistance, but only an indirect effect in that it is also a factor which determines the plate current. Upon an increase in the plate current, the inner resistance of the tube becomes lower, and the resonant circuit in the plate circuit is subjected to an ever increasing damping whereby the degree of the damping depends on the value of the plate potential. In considering these functions the inner resistance of the tube is to be assumed in parallel to the resonant circuit. By varying the plate current or the plate potential, or both, the selectivity of the resonant circuit, and hence that of the entire amplifier stage, can be adjusted in a very simple manner and within wide limits. The variation in the plate current may be effected by varying the negative control grid bias potential, or by varying the screen grid potential, or by varying simultaneously both values.

The above mentioned manner of controlling the band width has the advantage that the degree of amplification will be influenced to a comparatively slight degree only. For the degree of amplification V of a tube the following equation exists, as is known:

$$V = S \cdot \frac{R_a R_i}{R_a + R_i}$$

Not only does the inner resistance R_i depend on the plate current J_a , but also the mutual conductance S , and for the normal $U_a^{3/2}$ -characteristic, $S = a \cdot J_a^{1/3}$, wherein a is the constant of the steepness depending only on the construction of the electrode system of the tube. From these relations it can be readily seen that at an increase in the plate current J_a , the steepness S increases, while the inner resistance R_i on the contrary decreases. Since however, the steepness S increases with $J_a^{1/3}$, while at the same time the inner resistance R_i decreases, being inversely proportional to J_a , the degree of amplifica-

tion V of a tube measured at constant plate voltage U_a as function of the plate current J_a , must increase with an increase in J_a , and must attain a maximum at a definite plate current, 5 whose magnitude depends on the outer resistor R_a and on the product $(b \cdot U_a)$ in order again to decrease at a further increase in J_a . The shape 10 of the curve representing the amplification as function of the plate current, and the height of the maximum depend very considerably on the 15 shape of the $J_a \cdot U_g$ -characteristic (U_g =grid potential), i. e. on the variation of the steepness as function of the plate current, and can be influenced to a wide degree by varying the shape of 20 the characteristic (such as for instance in case of an exponential characteristic).

In the drawings, Fig. 1 shows the curves for the 25 degree of amplification and band widths measured in the case of a pentode, as function of the 30 plate current for various plate potentials. Fig. 2 shows a circuit embodying the invention, and Figs. 3 and 4 show modifications of the circuit. In Fig. 1, the band width plotted in any desired 35 units varies very considerably along these curves. At any small plate currents which are below the 40 value appertaining to the maximum of the curve for the degree of amplification, the selectivity of the resonant circuit connected to the anode is scarcely influenced at all by the inner resistance 45 R_i of the tube, since $R_i \gg R_a$. In this range the following equation is approximately valid,

$$V = S \cdot R_a$$

the amplification thus increasing approximately 50 proportional to $J_a^{1/3}$. In the proximity of the maximum of V , R_i is approximately equal to R_a , so that the band width of the resonant circuit, or to be more exact of the complex resistance formed by the resonant circuit and the tube, is 55 approximately doubled. If the plate current increases to a value which is approximately twice the current value appertaining to the maximum of the curve for the degree of amplification, then the band width is approximately three times its 60 original value, the stated figures being given only approximately for the sake of comparison, as the accurate values can be read from the curves.

In order to vary the band width the following 65 possibilities are available in accordance with the invention:

- (1) Plate potential U_a and screen grid potential U_s remain constant; control of the plate current J_a being effected by means of the control grid bias potential U_g .
- (2) Plate potential U_a and control grid bias potential U_g remain constant; control of the plate current J_a being attained by means of the screen grid potential U_s .
- (3) Plate potential U_a is constant; control of 70 the plate current J_a by means of the control grid bias potential U_g and by the screen grid potential U_s .
- (4) Plate current J_a remains constant; control by means of the plate potential U_a .
- (5) Simultaneous control of the plate potential, and of the plate current by one of the measures specified in 1 to 3.

For the sake of clarification several means of control are indicated in the Figs. 2 and 3. In 75 Fig. 2, the tube R contains a cathode K indirectly heated by the heating element H , a control grid G , the screen grid S and the anode A . It is assumed that secondary emission from the anode is prevented by a suitable surface treatment, or 80 spacing. The alternating potential to be ampli-

fied is applied to the input circuit R_g , while the amplified voltage is derived from the output circuit R_a connected to the anode. There is available a direct potential obtained from a battery or battery eliminator, and applied to the terminals 5 designated by + and -, and which is applied to the voltage divider P . The latter has connected thereto across the variable taps 1, 2, 3 and 4 the control grid, the cathode, the screen grid, and the anode. For control in accordance with case 1, 10 the tap means 1 is to be displaced, while the remaining tap points remain unvaried. In a corresponding manner, for an adjustment according to 15 case 2 only the tap means 3 is to be displaced. A simultaneous variation of screen grid potential and control grid bias potential (case 3) can be obtained either by displacing the taps 1 and 3, or only the tap 2. It is clear that for the fourth case the tap 4 is to be varied, while the fifth case represents a combination of the previously mentioned possibilities.

In Fig. 3 the same reference characters appertain to corresponding parts. The number of electrons about a retarding grid (suppressor grid) B is increased in order to suppress secondary 25 emission, said grid being directly connected with the cathode K as is usually done. A control according to case 4 can be carried out by introducing a variable resistor W in the plate circuit. In view of the high inner resistance of the tube the 30 variation of the plate current is negligibly small, so that only the variation in the plate potential will be effective. A control according to case 5 can be carried out, for instance, in that a fixed 35 ohmic resistor W is inserted in the anode line, having the effect that a variation of the plate current produced by one of the previously stated means, automatically also varies the plate potential, in a sense suitable for influencing the band width, in that upon an increase of the plate current, the plate potential decreases.

Finally, through special switching means, it can be accomplished that the degree of amplification remains exactly the same during the control of the band width. From Fig. 1 can be seen, 45 for instance, that at a plate current of $J_a \approx 4.5$ ma. there corresponds to a plate potential of $U_a = 200$ volts exactly the same amplification as for the plate potential $U_a = 100$ volts at a plate current of $J_a \approx 1$ ma. However, the band widths for these 50 two conditions have the proportion 1:2.

Herefrom it can be deduced that through simultaneous increase or variation of the plate current and plate potential a control of the band width can be obtained at exactly constant degree 55 of amplification. In practice this result may be approximated by varying the plate current by means of a series resistor situated in the screen grid circuit, and at the same time varying the plate potential by means of a variable series resistor in the anode lead-in, the latter variation being in such a sense that with an increase in plate current the plate potential increases. In place of a special series resistor, the same end 60 can also be attained by means of a voltage divider resistance in the respective circuits. As tests have shown, it is possible to derive plate potential and screen grid potential from the same voltage source, and to utilize a common series resistor, or a common voltage divider for the control of the plate potential and screen grid potential.

An example of construction is shown in Fig. 4. Here the same tube is used as in Fig. 2 whereby the voltages to be amplified are applied to the 75

control grid G, and the amplified power is derived from the plate circuit of said tube across the oscillation circuit R_a . The screen grid potential, and direct plate potential are supplied by a voltage source U_A common to both electrodes. In the common circuit of these two electrodes, the series resistor W_1 is inserted. Furthermore, fixed or variable resistors W_2 , W_3 may be provided to obtain different steady potentials for the anode and screen grid. The two last-mentioned resistors may sometimes be omitted (which is readily possible especially in pentodes, or other tubes in which the secondary emission is suppressed), so that the steady screen grid potential and steady plate potential are the same. The blocking condensers C_b , C'_b serve in the known manner to short circuit for alternating potentials.

The said measures for varying the selectivity may obviously also be automatically controlled by the wave to be received and amplified. For instance, the selectivity can be rendered a function of the amplitude of the oscillations to be amplified, in the sense that an increase in the amplitude, a decrease in selectivity occurs, and that in the absence of signals, the amplifier has a minimum band width, and hence the lowest sensitivity to disturbance. The automatic control may however, also take place in the opposite sense, in that a high selectivity corresponds with a large input amplitude. The detected voltage must of course be polarized in accordance with the desired type of control, i. e. in accordance as to whether the selectivity should increase or decrease with an increase in amplitude.

Figure 3 shows the case in which aside from a fixed negative control grid bias potential U_g , also a resistor W' is inserted in the input circuit of tube R , and across which the direct current component of the detected current is passed. In this case there appears at the resistor W' a potential drop, namely the control potential U_{gr} by which the plate current is influenced. In contrast to similar circuits in which the control of the degree of amplification is the end aimed at, the degree of amplification in this case remains approxi-

mately constant during the control performance in view of the fact that the working point is placed into the proximity of the maximum of the curve for the degree of the amplification.

What is claimed is:

1. In a receiver system, a tube having at least a cathode, signal grid, output plate and a positive screen electrode between the grid and plate, a source of signal modulated carrier energy coupled between the cathode and said grid, a resonant circuit connected between said plate and cathode, the circuit being tuned to the frequency of said carrier, means for varying the plate current and plate potential to adjust the magnitude of the tube inner resistance while maintaining the tube amplification constant and thereby to vary the degree of selectivity of said resonant circuit, and said tube being operated in the proximity of the maximum of the characteristic curve relating tube amplification to tube plate current. 20

2. In a high frequency signal amplifier network having a tube provided with a cathode, signal grid, positive screen and output plate, a tuned load circuit connected to the plate, a signal input circuit connected to the grid, and means 25 for simultaneously varying the plate current and plate potential of the tube in the same sense thereby to adjust the degree of selectivity of the load circuit while maintaining the tube amplification substantially constant. 30

3. In a high frequency signal amplifier network having a tube provided with a cathode, signal grid, positive screen and output plate, a tuned load circuit connected to the plate, a signal input circuit connected to the grid, means for simultaneously varying the plate current and plate potential of the tube in the same sense thereby to adjust the degree of selectivity of the load circuit while maintaining the tube amplification substantially constant, said varying means comprising a common direct current source for the screen and plate of the tube, and independent adjustable impedances connected between the screen and plate and the common current source. 40
